UNITED STATES PATENT OFFICE.

MOTIER L. JULIAN, OF MOUNT PLEASANT, IOWA.

WASHING-MACHINE.

SPECIFICATION forming part of Letters Patent No. 229,711, dated July 6, 1880.

Application filed April 5, 1880. (No model.)

To all whom it may concern:

Be it known that I, MOTIER L. JULIAN, of Mount Pleasant, in the county of Henry, and in the State of Iowa, have invented certain new and useful Improvements in Washing-Machines; and I do hereby declare that the following is a full, clear, and exact description thereof, reference being had to the accompanying drawings, and to the letters of reference marked thereon, making a part of this specification.

The nature of my invention consists in the construction and arrangement of a washing-machine, as will be hereinafter more fully set forth.

In order to enable others skilled in the art to which my invention appertains to make and use the same, I will now proceed to describe its construction and operation, referring to the annexed drawings, in which—

Figure 1 is a longitudinal vertical section of my washing-machine. Figs. 2 and 3 are detailed views of parts thereof.

A represents a box of any desired dimensions, supported upon suitable legs and provided with a lining, B, of zinc or other suitable sheet metal, covering the bottom and all four sides. This lining B is corrugated, as shown, to form a good washing-surface, and the corrugations on the sides may run either vertically or horizontally, or in any other convenient manner.

At one end the top of the box has a cross-bar, C, over which is attached the clothes-wringer D, and at this end of the box, at a suitable height, is hinged a rack, E, which is to support the tub when the wringer is used. When the rack is not in use it is folded close to the end of the box and held by a hook, a.

G represents the hinged lid of the box A, upon which is secured a metal frame, F, having a central hub, F', and through this hub is passed a vertical shaft, b, carrying upon its lower end, within the box, a reel, H, and on the upper end of the shaft is secured a bevel-gear wheel, I, as shown.

The frame F is provided with two vertical

sides, F² F³, and from the side piece F² projects an arm, F⁴, which forms a bearing for the upper end of the shaft b.

The side piece F³ has a vertical slot, x, and a guide-flange, d, on each side of the slot. Between these guides is placed a box, J, which also projects through the slot, and has side ribs, e, to enter notches y in the side piece F³. There are two sets of these notches for adjusting the box in two different positions.

Through the box J is passed a bolt, h, which also passes through an elongated hub, K, the opposite end of which fits in a groove on the inner side of the side piece F², and the bolt passes through a hole in the same, and is fastened by a nut, i.

The hub K forms a part of a double segmental gear, L—that is, a gear having two sets of cogs on concentric circles—and this gear is provided with a suitable lever for rocking the same.

There being two holes for the bolt h in the side piece F², and the box J being adjustable, as described, either set of cogs on the double gear L may be made to mesh with the bevel-gear I, and thus give greater or less speed to the reel H.

Having thus fully described my invention, what I claim as new, and desire to secure by Letters Patent, is—

In a washing-machine, the combination of a reel attached to a vertical shaft, b, having a gear, I, secured thereon, the double segmental gear L, with central bolt, h, the frame F, perforated side piece F², and the side piece F³, formed with the slot x, guide-flanges d, and notches y, and the movable box J, provided with the side ribs, e, all constructed substantially as and for the purposes herein set forth.

In testimony that I claim the foregoing I have hereunto set my hand this 9th day of February, 1880.

MOTIER L. JULIAN.
